FLUID DISPENSING APPARATUS

David Samiran, Fairfield, Ohio

Application November 14, 1938, Serial No. 240,353

4 Claims. (Cl. 221—67)

(Granted under the act of March 3, 1883, as
amended April 30, 1928; 370 O. G. 757)

The invention described herein may be manufactured and used by or for the Government for governmental purposes, without the payment to me of any royalty thereon.

5 The present invention relates in general to fluid segregating apparatus and more particularly to pressure feed fluid dispensing systems in which a separation of fluids of different density is obtained.

10 The invention relates in part to improvements in my Patent No. 2,120,266, issued June 14, 1938, and further illustrates two additional pressure dispensing systems in which fluid impelling or flowing means other than that intended for con-
sumption is employed to deliver a fuel such as gasoline to and or from fuel tanks in direct connection with internal combustion engines.

15 In the first system illustrated below, I deal with the underground storage tanks and utilize the two alternately repeating steps of driving water initially contained in one of such tanks into a waste drain through replacement introduction of gasoline from a railway tank car or equivalent supply source, then of driving the newly introduced gasoline line from said tank to servicing pits such as those provided in connection with any modern flying field by re-introduction of water into said tank from any suitable pressure source. The rate at which the latter step advances is regulated by

20 the amount of usage of the discharge mechanisms (such as "14" of my Patent No. 2,120,266); i. e., the amount of fuel "serviced" from the aforesaid pits. In the second system illustrated below, I have not elected to show initial presence of 25 water in the storage tanks. For simplicity's sake, the tanks are assumed to be empty prior to their initial filling with gasoline on the ground. Once in the air, the second step noted in my first illustrated system is utilized to effect air delivery of fuel from storage tank to consuming engine; i. e., water pumped from a lighter-than-air craft water recovery system is utilized to impel fuel from storage tank to engine carburetor. While dump valves are shown for ground emptying of water filled storage tanks, it is at once apparent that such emptying can equally well be accomplished by introduction of the double acting segregator forming part of my first illustrated system. In addition to the above two systems, 30 I have further illustrated below application of the aforesaid double acting segregator (of Fig. 5) to the fluid dispensing apparatus of my Patent No. 2,120,266 issued June 14, 1938.

35 The novelty for the first illustration of my invention resides in the installation of a single tank

double acting segregation system underground in such a manner that for one setting of the valves controlling its piping system, "top tank" introduction of gasoline or equivalent fuel from a railway tank car or equivalent source causes "bottom tank" withdrawal of water into an awaiting drain pipe. At the instant of complete water egress, the segregator element stops further fluid flow. Thereafter, the aforesaid valves are reset for service pit delivery of gasoline to the flying field. As before, at the instant of complete gasoline egress, the double acting segregator element stops further fluid flow. A level gauge is also provided for secondarily indicating "gasoline full" or "water full" storage tank condition.

40 The second illustration of my invention finds new and novel application to segregation systems adapted for use in fuel supply systems of lighter-than-air craft. It is well known to those skilled in the art that in lighter-than-air craft, it is necessary to use water ballast tanks which are for the purpose of maintaining a proper static equilibrium. In large craft of this character, a water recovery system is generally used which includes a condenser connected to the exhaust of each internal combustion engine. By means of the aforesaid condensers, moisture from the engine exhaust gases is condensed and delivered either by gravity action or a pumping unit into the water ballast tanks. Thus, while continued 45 engine operation tends to make the aircraft lighter, the water recovered in the above manner will substantially equal weight loss due to fuel consumption.

45 A further serious drawback is present in systems of the above character. Ballast tanks are employed which form a system separate and distinct from the fuel supply system. This added structural weight materially reduces the carrying capacity of the aircraft. Consequently, the useful 50 load is substantially reduced.

The primary object, therefore, of the second illustration of my invention is to provide a combination fuel supply-water ballast system in which the fuel supply tanks are utilized to serve a dual purpose; i. e., to initially supply fuel to the carburetors of the power plant and thereafter to function as ballast tanks, thus saving weight increase which would otherwise result from adding independent tanks to the water recovery system 55 of lighter-than-air craft. This is particularly advantageous in large dirigibles, such as the naval aircraft *Akron*, in which the ballast tanks weighed in the neighborhood of 3000 pounds. By eliminating such unproductive weight, a substantial 60

increase in useful load is effected, a larger fuel tank capacity is possible permitting of a greater cruising range, greater structural simplicity in the design of the aircraft is effected through elimination of extra tank supports, and many other advantages accrue which those skilled in the art will readily recognize.

A further object of the second illustration of my invention is to provide a system in which pressure head of the water recovered is utilized to force the fuel stored in the supply tanks into the carburetors of the power plant.

A still further object of the second illustration of my invention is to provide, in a system of this character, a segregator unit of the type set forth in my invention Patent No. 1,700,811, issued February 5, 1929, so located with respect to the fuel supply tanks and the carburetors of the power plant that a complete segregation of the gasoline and water is effected, thus eliminating the hazard of the water used for ballast and propulsion purposes from reaching or entering into the carburetors of the power plant.

Another object of the second illustration of my invention is to provide, in a system of this character, a signaling device adding an additional improvement to the signaling device set forth in my Patent No. 2,069,279, issued February 2, 1937. My improved device operates in such a manner as to assure continuation of fuel flow after indication has been given to the pilot of the aircraft that the fuel supply in any one or more tanks is exhausted. This device is so constructed that a predetermined lapse of time is available, after visual signal is given to the pilot advising him of the exhausted condition of a tank, in which to turn on a new fuel supply from another tank.

I also wish to apply the new and novel double acting segregation feature illustrated above to the improvements in fluid dispensing apparatus disclosed in my Patent No. 2,120,266, issued June 14, 1938. For that reason, I have added a third illustrated system below.

With the foregoing and other objects in view, the invention consists in the novel construction and arrangement of elements described, illustrated, and claimed, it being understood that other modifications may be made within the scope of the claims without departing from the spirit of the invention.

Referring to the drawings, in which like parts are designated by like numbers:

Fig. 1 is a diagrammatic representation, in partial cross-section, of my first described system;

Fig. 2 is a partial showing of Fig. 1 with improved piping-valve arrangement;

Fig. 3 is a diagrammatic representation of my second described system with water ballast and fuel tanks in "take-off" condition;

Fig. 5 is a cross-sectional view of the double acting segregation element which is commonly employed in the first, in the second and in the third described systems of Figs. 1 and 2, Fig. 3 and Fig. 4, respectively;

Fig. 6 shows in detail the expansion tank employed in Figs. 1 and 2;

Fig. 7 shows a segregation element internally similar to the double acting segregation element of Fig. 5, except that the scale of the last mentioned element is reduced and that there is further simplification of its lower piping arrangement;

Fig. 8 shows in detail a signal element employed in my second described system of Fig. 3;

Fig. 9 is a diagrammatic representation of the

ballast tank and fuel tanks of Fig. 3 under one-fourth completed flight condition; and

Fig. 10 is a diagrammatic representation of the ballast tank and fuel tanks of Fig. 3 under one-half completed flight conditions.

The principal elements composing my single tank double acting segregation system (shown in whole or part in Figs. 1, 2, 5, 6 and 7) consist of an underground storage tank 10, an associated control station 12, a gasoline fill line 14 from a nearby tank car siding or the like (not shown), a water pressure line 16 from any suitable source (not shown) and a system of pipe lines-controls 18 associated therewith.

In my first described system, I employ fluid pressure to accomplish fuel delivery in much the same manner as in my Patent No. 2,120,266, issued June 14, 1938. Water from the pressure line 16 enters the storage tank 10 through an inverted stand pipe 20, the lower end of which 20 is disposed a short distance above the lowest level of the storage tank 10.

The auxiliary parts associated with the major assemblies referred to above are outlined below. The pressure line 16 is provided with pressure gauges 22 and 24, having remote reading dials 26 and 28 located in the control station 12 for indicating initial pressure head available and secondary controlled pressure head. Water is introduced or cut off by means of a hand valve 30 having a wheel portion 32 located above a main floor A of the control station 12. As a precautionary measure, the pressure line 16 is further provided with a pressure regulating valve 34. Intermediate of the pressure regulating valve 34 and the stand pipe 20, I place an emergency shut-off valve 36, an electrically operated valve 38 provided with a remote control switch 40, and a pressure relief valve 42 positioned to overflow into the drain 44 of a pit B (located in the control station 12) for further controlling water pressure prior to its entry into the storage tank 10. I also provide an auxiliary hand valve 46 for controlling the passage of water into the tank 10 in the event that the electrically operated valve 38 should fail to function. This valve is operated from sub-floor C of the control station 12. I have thus provided not only control of the quantity of water introduced into the storage tank 10, but have also provided means 50 for closely regulating the pressure of all water so introduced.

It will be further noted that a by-pass line 48, connecting the auxiliary hand valve 46 with the stand pipe 20, and a main feed line 50, similarly connecting the electrical valve 38 with the stand pipe 20, are also commonly interconnected with a lower portion 68b of the segregator 18 by means of a pipe 52 provided with a hand valve 54. The pipe 52 corresponds to the upper end of the pipe 472 of Fig. 4, the functions of which are described in detail below, it being sufficient for the present to note that the hand valve 54 is placed therein to prevent draining of water through the segregator 18 and a second pipe 56 (outlet passage 522 of Fig. 4) into the drain 44 provided in the pit B.

In order to provide for ingress and egress of gasoline, the storage tank 10 is equipped at its uppermost surface with a combined nipple and T 58. It will be noted that the nipple-T 58 is jointly interconnected to the inlet side of a passage 68a of the segregator 18 by means of a pipe 62 provided with hand valve 64 and to the fill line 14 through a check valve 66 permitting 76

only ingress of gasoline from a nearby tank car or the like (not shown).

The segregator 18 is provided at the outlet side of the passage 60a with a delivery line 68, 5 which, in this particular embodiment of my invention, is connected to the inlet side of a passage 70a of an auxiliary segregator unit 72. The auxiliary segregator 72 is provided as a safety measure to safeguard against failure or even 10 partial failure of the main segregator 18.

The delivery line 68 is further interconnected with an expansion tank 74 located above the main floor A of the control station 12 by means of commonly connected L-shaped pipes 76a and 15 76b. It will be noted that the pipe 76b is connected to the near uppermost surface of the expansion tank 74 in order to make certain that a predetermined quantity of incoming fluid will always be trapped therewithin. The lower level 20 of the expansion tank 74 is substantially coincident with the lower level of the tank car or equivalent container heretofore mentioned. The far lowermost surface of the expansion tank 74 is connected to the fill line 14 by means of a 25 check valve 78, a pipe 80 connected thereto, and a pipe 82 with lower end directly connected to the fill line 14. At the junction of the aforesaid pipes, I provide an air vent pipe 84. It should be noted that the check valve 78 is arranged to readily permit fluid in the expansion tank 74 to drain into the fill line 14 through 30 previously mentioned interconnecting pipes, but to positively prevent any "backing up" of such fluid from the fill line 14 into the expansion tank 74. The upper end of the vent pipe 84 is provided with a check valve 86 serving to retard fluid overflow through a vent opening 88 terminating the open end of the vent pipe 84. The uppermost portion of the far end of the 35 expansion tank 74 is further interconnected to an upper portion of the vent pipe 84 by means of an auxiliary vent pipe 90 of limited flowing capacity.

Intermediate of the junction of the fill line 40 14 and the pipe 82, and the nipple-T 58, I provide a hand valve 92. I thus incorporate positive means for connecting or disconnecting the storage tank 10 from its initial source of fuel supply. I further provide a hand valve 94 at 45 the junction of lines 76a and 76b such that fluid flow from the delivery pipe 68 may be connected with or cut-off from the expansion tank 74. In a similar manner, I have provided additional hand valves 96 and 98 in the pipes 52 and 56 50 leading, respectively, into and out of the passage 60b provided at the bottom of the segregator 18, in order that drainage therefrom may be readily accomplished into the pit B. Reasons for the latter installation will be dealt with, 55 below, in connection with the detailed description of the segregator 18.

It will be noted that the auxiliary segregator 60 72 is provided with a separate pit D from which pipe lines extend to a plurality of servicing pits 100 located upon the flying field. Three hand valves 102 control single fuel ingress into and 65 dual fuel egress out of the auxiliary segregator 72. The bottom of the pit D is suitably interconnected with the drain 44 of the pit B located 70 in the control station 12.

The tank 10 is also provided with a liquid level 75 gauge composed of a float element 104 (non-buoyant in gasoline) located within the tank 10 and a dial element 106 located in the control station 12 for remote reading of said element.

An air vent 108 is further provided between the uppermost surface of the tank 10 and the pipe 62.

The operations of the fuel dispensing system shown in Fig. 1 are described with reference to three distinct "tank conditions." Assuming, in 5 all cases, an initially "closed valve" condition for both hand and electrically controlled valves, these operations are as follows:

Empty storage tank

Standing on floor A of the control station 12, the operator first opens hand valves 64 and 94. This is done in order that air trapped within the tank 10 may be directly vented to the atmosphere through the vent pipe 108; pipes 62, 68, 76a 15 and 76b; the expansion tank 74; and final pipes and opening 90, 84 and 88. It is assumed, above, that the segregator 18 is empty, under which conditions it is obvious (upon reference to Fig. 5) that the pipes 62 and 68 are in unobstructed communication with one another. The operator next 20 opens the hand valve 92, permitting fuel from a tank car or equivalent source to commence to flow through the check valve 66, the fill line 14, the open valve 92 and the nipple-T 58 into the 25 tank 10. The operator has but to watch the dial element 106 located on floor A of the control station 12 to ascertain when the tank 10 has become 30 completely filled with gasoline, necessitating closing of the valve 92. In order to avoid possible confusion in connection with the second "tank condition" noted below, let it be assumed at this point that the operator closes hand valves 64 and 94, thus terminating further venting of the tank 10 directly to the atmosphere. 35

Gasoline filled storage tank

The tank 10 is now in condition for servicing of the pits 100 forming part of the flying field. Still remaining on floor A of the control station 12, the operator first closes the switch 40, thus 40 automatically opening the electrically operated valve 38. This operation leaves an unobstructed path from the latter valve through the feed line 50 and the stand pipe 20 into the lowermost portion of the tank 10. Having next opened the hand valve 64, thereafter the operator opens the hand valve 30 permitting water from the pressure line 16 to flow through the pressure gauge 22, the pressure regulating valve 34, the emergency shut-off valve 36 and the above mentioned 45 unobstructed path into the tank 10. Upon introduction of the aforesaid water pressure within the storage tank 10, gasoline is ejected through the nipple-T 58, the pipe 62, the segregator 18, 50 and the delivery line 68; up to the pit 100. The operator must then leave the control station 12 a sufficient time to open the three valves 102 located in the pit D, in order that gasoline may 55 continue to flow through the auxiliary segregator 12 and from thence to the servicing pits 100 located upon the flying field. 60

Continued servicing of aircraft at the pits 100 ultimately causes substantial water replacement of space previously occupied by gasoline within 65 the tank 10. When the former has attained a level sufficient to overflow through the nipple-T 58 and the pipe 62 into the segregator 18, the float 162' located therewithin will immediately rise to the position indicated in Fig. 7, whereupon further flow through the valve seat 158' is prevented by seating of upper conical valve 168'. Obviously, thereafter, no further supply of fuel may be drawn from the servicing pits 100. In actual practice, the water is rarely allowed to rise to the 70 75

aforesaid level. The operator may readily ascertain by reference to the indicator element 106 of his fuel level gauge when the proper time has arisen for ejection of water by a fresh supply of gasoline from a tank car or other equivalent source.

Water filled storage tank

To replace the water filled tank 10 with gasoline, the operator first opens the switch 40, thus 10 automatically closing the electrically operated valve 38 or he may, if he so desires, close the hand valve 30. He thereafter closes the hand valve 64 in the pipe 62, after which he opens the hand valve 82 of the fill line 14, the hand valve 54 of the pipes 50 and 52, and the hand valve 98 of the drain pipe 56.

The foregoing valve settings accomplish two results; i. e., they provide for unobstructed egress of water through the stand pipe 20 and the lines 20 52 and 56 directly into drain 44 of the pit B, and also provide a constantly increasing top layer of gasoline, assuring water egress flow through the bottom of the stand pipe 20. Ejection of water continues until the top layer of gasoline reaches 25 the lower end of the stand pipe 20. Then, for a very brief period, a mixture of water and gasoline will enter the bottom of the segregator 18 until a sufficient quantity of the latter causes 30 the lower conical valve 172 to seat as indicated in Fig. 5, thus cutting off further fluid flow through the outlet 150b of the passage 60b. It should be noted, at this point, that the operator need not delay closing of the hand valve 92 until the final 35 stage discussed above. Reference to the indicating element 106 will accurately disclose to him when the bottom level of the downwardly travelling gasoline layer is about to approach the open end of the stand pipe 20. The hollow or cork portion of the float element 104 is designed to 40 float in water, but to sink in gasoline, the element 106 reading clockwise for "empty-to-full water" content and counter-clockwise for "empty-to-full gasoline" content. Having effected stoppage of incoming gasoline through the 45 fill line 14, the operator thereafter completes closure of the hand valves 54 and 98. Thereafter, the operation described immediately above for the gasoline filled storage tank is repeated, etc.

The latter two of the above three enumerated 50 storage tank conditions cover normal operation of the first embodiment of my invention. There is a special condition incident to water filled storage tank operation worthy of note, at this time, because of a certain degree of internal pressure which is built up within the tank 10 when 55 the water level has dropped substantially to the half-way mark. I realize the necessity for relieving the aforesaid undesirable internal pressure by some suitable means. This I propose to 60 accomplish in two ways.

Upon reaching the half-way mark, the water will continue to be forced upwardly through the stand pipe 20 and into the lower passage 60b of the segregator unit 18. Entry of water into the 65 lower passage 60b of the segregator unit 18 forces the gasoline in that unit through its upper passage 60a and into the pipes 76a and 76b; it being understood that the hand valve 94 is open at this 70 time and that the hand valve 64 was closed prior to opening of the hand valve 94. It is also essential for the proper function of the above installation that the hand valve 64 should always be closed prior to opening of the hand valves 54 75 and 98. This is necessary for the following

reason: Assuming the hand valve 64 to be first closed and the hand valves 54, 94 and 98 to be thereafter opened; it is readily apparent that the water flowing through the pipe 52 into the lower passage 60b of the segregator unit 18, by reason 5 of the built up pressure in the tank 10, forces the gasoline contained within the segregator 18 into the expansion tank 74 through the lines 76a and 76b until such a time as the water entering the float chamber 142' causes the float 162' to move 10 upwardly into the position illustrated in Fig. 7, causing seating of the upper conical valve 168'. Under these conditions, were the valve 92 opened, the gasoline in the expansion tank 74 would readily flow from this tank through the pipes 80, 15 82 and the nipple-T 58 into the storage tank 10. This increase in the head of gasoline in the pipes 80 and 82, together with the head of gasoline then existing in the storage tank 10 would have a tendency to over-balance the head 20 of water in the stand pipe 20, consequently a further discharge of water would take place through the hand valves 54 and 98 of the segregator unit 18. If, under such conditions, the hand valve 92 were to be opened, it is readily 25 apparent that the pressure head of gasoline between a tank car or equivalent and the storage tank 10 would cause gasoline to flow into the expansion tank 74, displacing the water remaining therein, until such time as the gasoline rises 30 in the stand pipe 20 and enters the segregator 18 through the pipe 52, at which time lowering of the float 162 shuts off the lower conical valve 172, as shown in Fig. 7. Thereupon, the system is 35 ready for changed operation under the gasoline filled storage tank condition, providing the hand valves 92, 54, 94 and 98 are first closed and the hand and electric valves 32, 38 and 64 are thereafter opened.

Let it be assumed that the hand valve 64 is 40 open, the hand valve 92 is closed, the hand valves 54, 94 and 98 are open, and that the tank 10 under partially built up pressure due to half level 45 of water in the tank. Under such circumstances, it is readily apparent that the aforesaid built up pressure will force the gasoline through nipple-T 58, the pipe 62, the upper passage 60a of the segregator unit 18 and into the expansion tank 74 through the pipes 76a and 76b. During the above, it is of course assumed that the lower 50 conical valve 172 of the float 162 in the segregator unit 18 is seated and consequently the water cannot pass through the valves 54 and 98. Under these conditions, if it is desired to refill the storage tank 10, the hand valve 64 must first be 55 closed. Subsequent opening of the hand valve 92 permits the gasoline to flow from a tank car or equivalent through the fill line 14 into the storage tank 10. At this instant, the gasoline rising in the vent pipe 84 corresponds in height to 60 the head of gasoline in the tank car or equivalent. This head of gasoline is prevented from entering the expansion tank 74 by reason of the location of the check valve 78.

Continued flow of gasoline into the tank 10 65 will cause a like volume of water to be displaced therefrom. Upon entering the segregator 18, the displaced water will force a like quantity of gasoline from the segregator 18 into the expansion tank 74 until such time as the level of water 70 in the float chamber 142 is such as to cause the float 162 to rise and close the upper conical valve 168. At this time, with the lower conical valve 172 unseated, the water is permitted to readily flow through the valve 98 and into the drain 44 75

of the pit B. When the lowering level of gasoline in the tank car or equivalent has reached the upper level of gasoline trapped within the storage tank 74, gasoline within the latter is permitted to flow from the tank 74 through the pipes 80 and 82 into the fill line 14 and from thence into the storage tank 10.

The second way in which I propose to eliminate the aforesaid undesirable internal pressure in the storage tank 10 consists of inserting a manually operated drain valve 96 at the base of the pipe 52.

Before proceeding with the description of the second illustration of my invention, I wish to deal briefly with the simple valve and piping rearrangement of my Fig. 2 whereby I accomplish two marked improvements over the disclosure of Fig. 1, as well as description of Figs. 5, 6 and 7.

My first improvement is concerned with the placement of a by-pass line 110 having a hand valve 112a between former pipings 62 and 68 such that gasoline entering the nipple-T 58 may be completely by-passed around the segregator 18. Two additional hand valves 112b and 112c are installed on either side of the segregator passage 60a. Opening of the hand valve 112a, in conjunction with closing of the hand valves 112b and 112c, makes possible emergency delivery of gasoline from the tank 10 to the service pits 100 (through the auxiliary segregator 72). I thus provide for servicing or repair of the segregator 18 without interruption of the gasoline supply to the flying field. A pet cock 114, added at the top of the passage 60a, aids drainage of the segregator 18 when the hand valves 112b and 112c are closed, etc.

In my second improvement over the disclosure of Fig. 1, I seek to materially reduce the number of valve hand adjustments required for the latter two of the three "tank conditions" enumerated above. Assuming a continuously open condition of the hand valve 92 (because it is "backed up" by the check valve 66), I need only to incorporate a unitary control 116 having an operation wheel 118 for use in conjunction with former remote control switch 40 to permit an operator to completely control my segregation system from floor A of the control station 12. In addition to the wheel 118, the unitary control 116 consists of a pedestal 120 secured to the floor A by means of the structural members 122, a horizontal axle 124 fixed to the wheel 118 such that its ends project through the upper portion of the pedestal 120, a sprocket 126 fixed to the mid portion of the axle 124 and sprocket chains 128 and 130. Referring to floor level C, I first remove the two hand wheels of the formerly vertically disposed valves 64 and 94 and thereafter so inwardly tilt them that their valve stems are coaxial. This makes possible replacement of two discarded hand wheels with a tandem toothed sprocket 132. When so tilted, tandem toothed sprocket rotation will effect simultaneous opening of one and closing of the other (or vice versa) of the valves 64 and 94. It will be noted that the near tooth disc of the tandem toothed sprocket 132 is operably connected with the sprocket 126 by means of the sprocket chain 128. By the further simple expedient of relocating former hand valve 54 on the horizontal portion of the pipe 52 such that its stem is parallelly disposed with reference to the stems of tilted valves 64 and 94 and by further relocation of former hand valve 98, such that its stem lies parallel to and immediately beneath the tilted stem of tilted valve 94, I am able to

simultaneously drive all four valves through added sprocket chain 130 interconnection with the far tooth disc of the tandem toothed sprocket 132 and two additional sprockets 134 and 136 replacing removed hand wheels formerly fixed to the ends of the vertically disposed hand valves 54 and 98. To assure more rigid mounting of the relocated valve 98, I have provided a pedestal 138 and U-bolts 140 for holding the bent back portion of relocated pipe 56.

The operations of the fuel dispensing system shown in Fig. 2 are described with reference to the latter two of the three "tank conditions" discussed in connection with Fig. 1. The initial "tank condition" is met with but once, upon original installation of the system. It so nearly parallels the adjustment features of Fig. 1 as to need no further comment, hereafter. Brief attention is invited, however, to certain "special" settings of the following valves: The hand valve 112a should only be open during the initial filling of "Empty" tank 10 with gasoline. Thereafter, it should always remain closed, except when it is desired to by-pass gasoline around the segregator 18 directly into the segregator 70. The hand valves 112b and 112c should always remain open with the single exception of the by-passing period just mentioned. The hand valve 30 is assumed to remain open, since no water pressure or flow can occur until either the hand valve 46 or the electric valve 38 are opened. Obviously, lack of space precludes re-showing these valves in Fig. 2. Since the hand valve 92 is "backed up" by the check valve 66 (preventing any backward flow of gasoline in the pipe 14), that valve is assumed to remain open. The three valves 102, in the pit D, are also assumed to remain open.

Gasoline filled storage tank

Considering all rotational movements of the operating wheel 118 to be made with reference to its back face (as viewed by an operator), the operator first accomplishes complete counterclockwise rotation thereof. This effects simultaneous opening of tilted valve 64 and closing of tilted or relocated valves 94, 54 and 98, thus removing all obstructions to gasoline egress from the tank 10 through path 58, 64, 112b, 62, 60a, 112c, 68, 102, 70a and 102. Thereafter, the operator closes the switch 40, which still further removes all obstructions to water ingress into the tank 10 through path 16, 22, 30, 34, 36, 38, 50 and 20. Gasoline may now be drawn at will from the service pits 100. Simply referring to the dial 106 will indicate when a condition of "water full" has been reached, necessitating the adjustment noted below.

Water filled storage tank

The operator first opens the switch 40, thus terminating further water ingress into the tank 10. He then accomplishes complete clockwise rotation of the hand wheel 118. This effects simultaneous opening of relocated or tilted valves 94, 98 and 54 and closing of tilted valve 64, thus removing all obstructions to water egress to the drain 20 of the pit 44 through path 20, 54, 52, 60b, 56 and 98. Since the hand valve 92 is normally always carried in open condition, no obstruction exists to immediate ingress of gasoline into the tank 10 through path 66, 14, 92 and 58. By reference to the dial 106, the operator may exactly ascertain when a "gasoline full" condition of the tank has been attained, necessi- 75

tating repetition of the adjustment noted above.

In Figs. 5 and 7, I show full and partial cross-sectional views of the segregators 18 and 72 employed in Figs. 1 and 2. Except for size reduction, the internal structure of the segregator 72 is a duplication of the internal structure of the segregator 18. For that reason, reduced scale parts bear the number designation of full scale parts (plus added prime designation). Due to replacement of former pipe 52 by a plug 152b, the unit 72 functions solely as a "single acting" segregator.

The exterior of the segregator 18, as shown in Fig. 5, is composed of a casing 142, which includes a removable top plate 144, and a float chamber 146 secured together in any conventional manner rendering the same liquid-tight. The structurally like passages 60a and 60b of the segregator 18 are provided with inlets 148a and 148b, and outlets 150a and 150b. Both inlets are tapped to receive, respectively, pipes 62 and 52. In like manner both outlets are similarly threaded to receive pipes 68 and 56. The passage 60b is provided with a plug 152b. In addition to plug 152a, the passage 60a is provided with a pet cock 154 tapped into the upper plug surface. The interior of the chamber 146 is provided with deflectors 156a and 156b. The deflector 156a is fixed to the lowermost surface 40 of the outlet 150a by means of a threaded valve seat 158. The deflector 156b is fixed to the uppermost surface of the outlet 150b by means of an upstanding combination float and valve guide 160 with lowermost collar internally and externally threaded. A float 162 is provided with a central guide tube 164 adapted to freely slide on the outer diameter of the upstanding guide 160, and a filled plug 166. There is further fixed to the uppermost surface of the float 162 an upper conical valve 168. A bearing pin 170 protrudes laterally from the base of the upper conical valve 168 for supporting a lower conical valve 172, valve stem 174 and valve stem adjusting nut 176. The lower conical valve 172 is shown in contact with a valve seat 178 screwed fast to the inner threaded portion of the upstanding guide 160 prior to assembly of the deflector 156b, which is further provided with a drain hole 180. The interior of the chamber 146 is completed by installation of a sieve 182 between the flanged outer portions of the deflectors 156a and 156b.

Since the segregator 72 is provided solely as a safety measure against failure of the main segregator 18, a plug 152b' (sealing the inlet 148b') replaces the pipe 52 of segregator 18. In like manner, the open end of the T holding the J-shaped over-flow pipe of outlet 150b' is sealed by a second plug 152b' instead of being connected to piping similar to the pipe 56 of segregator 18.

In Fig. 6, I show a cross-sectional view of the expansion tank 74 of Figs. 1 and 2. It is composed of a casing 184 provided with tapped bosses 186 and 188 (for reception of pipes 76b and 80, respectively), a fixed header 190, and a removable header 192 provided with tapped boss 194 (for reception of pipe 90).

Before detailed comment as to assembly and operation of the segregators 18 and 72, a brief preliminary statement is in order. I seek segregation of a predetermined heavier liquid or reference medium from a preselected lighter liquid of appreciably less density. Therefore, prior to assembly of the float 162 (including upper

and lower conical valves 168 and 172, as well as the plug 166), I place the float 162 in any vessel containing a sufficient quantity of the above reference medium to completely immerse the same. I control the depth to which the float 162 freely sinks in the above reference medium by the introduction of a column of liquid C, of h height, within the inner cavity of the float 162. This causes a very carefully predetermined upper portion of the float 162 to remain exposed 10 above the top of the indicated level l_1 of the aforesaid reference medium in accordance with the teachings of my Patent No. 2,078,977, issued May 4, 1934. Following "tightening down" of the plug 166, the float 162 is ready for removal 15 from the above vessel and assembly within the chamber 146, as shown in Fig. 5. The sieve 182 is next loosely placed within the deflector 156b and the assembled upper portion of the casing 142 thereafter capped over and sealed to the 20 chamber 146.

Operation of the segregator 18 may be very briefly stated. With the casing 142 initially empty, resulting in the float 162 being in the "down" position, shown in Fig. 5, liquid A (such as water 2 from the pressure line 16 of Fig. 1) is introduced through the inlet 148b and permitted to rise exactly up to the level l_1 (of Fig. 5). The float 162 is thereupon "just" free floating; i. e., it is weightless with reference to its valve seat 30 178. If, however, liquid B (such as gasoline 35 from the feed line 14) is thereafter introduced through inlet 148a, the float 162 will immediately move into the "up" position of Fig. 7 in accordance with the teachings of my Patent No. 2,078,977, resulting in immediate closure of valve seat 158. For the mere purpose of illustration (in Fig. 5), I have chosen the joining levels l_2 of the liquids A and B such that the float 162 is exactly at a state of equilibrium therebetween; i. e., although the lower conical valve 172 is shown in contact with the valve seat 178, no pressure is exerted by the former upon the latter. It must therefore follow, in all future operations of the segregators 18 and 72, that 40 progressive risings of the joining levels l_2 above the showing of Fig. 5 will cause initial unseating of lower conical valve 172 and will thereafter cause the float 162 to continue to rise upwardly to the point of seating of the upper conical valve 168 within the valve seat 158. On the other hand, progressive lowerings of the joining levels l_2 of Fig. 7 will effect an exact converse of the above, terminating in the "down" float positioning of Fig. 5, attended by seating 50 of the lower conical valve 172.

The purpose of installing special duplicate passages (60a and 60b) in my segregator 18, in combination with certain further special piping and valve interconnections (as shown in Fig. 5), may 60 now be readily disclosed. In both segregators, interaction of the inlets 148a-148a', the outlets 150a-150a' and the (lower) outlets 150b-150b', under conditions of "down" float, are identical; i. e., normal segregation of two liquids of different density. However, by installing an entirely new water inlet and extra capacity water outlet at the bottom of the segregator 18 (by means of the valves 54-58 and the pipes 52-56) and by further providing the pipe 62 of the inlet 148a with a shut-off (by means of the valve 64), I am able to use my segregator 18 as an automatic control in connection with ejection of water from the tank 10 to the drain 44 by means of ingress of gasoline from a tank car or equiv- 75

alent. The reason for this is readily apparent. As long as the casing 142 contains a predominance of water, the float 160 will remain in the "up" position of Fig. 7 and no restriction exists 5 between the inlet 148b and the outlet 150b of the passage 60b. However, with dropping of the lower level of incoming gasoline below the bottom of the stand pipe 26 (of the tank 10), a predominance of gasoline will obtain within the 10 casing 142, causing the float 160 to drop to the "down" position of Fig. 5, resulting in stoppage of liquid flow through the outlet 150b of the passage 60b. As previously stated above, proximity to "gasoline full" tank condition is always 15 readily ascertainable by an operator through reference to the indicating element 106 of his fuel level gauge.

The principal elements of my second described system (shown in whole or part in Figs. 3, 8, 9 20 and 10) consist of an aircraft engine 210 equipped with a water recovery system 212 and conventional carburetor 214, a water ballast tank 216, a pump 218 for boosting water from the recovery system 212 to the ballast tank 216, fuel-water tanks 220 and 222, a segregator 224, a combination auxiliary tank and fuel level signal device 226 (partially detailed in Fig. 8), a system of pipe lines-controls 228 associated with the aforesaid principal elements, and a gasoline 25 fill line 230 commonly connected to the fuel-water tanks 220 and 222 and provided with a shut-off valve 232.

In the above system, I employ water or gasoline under pressure to accomplish gasoline or 30 water egress from storage tanks in the same manner as in my first described system. During free flight conditions, water from the elevated storage tank 216 (or directly from the pump 218, if a pressure by-pass is employed to 35 create an equivalent pressure head) is introduced at the lowest levels of the fuel-water tanks 220 and 222 to eject fuel from the highest levels thereof into the pipe lines-controls 228 and from thence to a point of consumption. On the other 40 hand, under mooring mast conditions, gasoline from a railway tank car or equivalent source is pumped through the fill line 230 and introduced at the highest levels of the fuel-water tanks 220 and 222 to eject water from the lowest levels 45 thereof into the pipe lines-controls 228 and from thence to any suitable waste container or drain located upon the ground beneath the lighter-than-air craft.

In the diagrammatic showing of Fig. 3, the 50 water storage tank 216 is provided with a vented filler cap 234, a water inlet 236 and a water outlet 238. The structurally similar fuel-water tanks 220 and 222 are composed of casings 240a and 240b, having respectively combination filler 55 cap-float controlled overflows 242a and 242b (with float elements shown in closed position), water inlets 244a and 244b, upper fuel outlets 246a and 246b (corresponding to the nipple-T 58 of Figs. 1 and 2), and lower (gravitational) 60 fuel outlets 248a and 248b. In addition to the above inlet and outlets, the casing 240b is provided with a second fuel-water inlet in the form of an inverted stand pipe 250 similar in character to the stand pipe 20 (of Figs. 1 and 2). 65 Before proceeding with the detailed description of the segregator 224 and the combination auxiliary tank and fuel level signal device 226, a brief description of the pipe lines-controls 228 is in order. The outlet portion of the pump 218 is connected to the water inlet 236 of the water

storage tank 216 by means of a pipe 252. Thus, any accumulation of moisture within the water recovery system 212 is immediately transferred to the water ballast tank 216. Since the water recovery system 212 is maintained empty, prior 5 to initial take-off of a lighter-than-air craft from its airdrome, the water ballast tank 216 must be manually filled to the arbitrary priming level l_3 with liquid A (i. e., water introduced through the vented filler cap 234). With take-off, the 10 level l_3 may slightly decrease depending upon atmospheric conditions encountered during flight and the efficiency of the water recovery system.

Interconnection of the fuel-water tanks 220 and 222 with the water ballast tank 216 is ac- 15 complished as follows: A vertically disposed pressure line 254, performing a function identical to the water pressure line 16 (of Figs. 1 and 2), is connected to the water outlet 238 of the water ballast tank 216. It is provided at its 20 upper end with a valve 256 and at its lower extremity with a second valve 258 (the first in open and the second in closed position). A short horizontal pipe 260 provides intercommunication between the pressure line 254 and the water inlet 244a of the fuel-water tank 220. If desired, the pipe 260 may be replaced by a duplicate of the inverted stand pipe 250 connected at its upper exposed end to the near side of the valve 256. A second horizontally disposed pipe 262 25 joins the pressure line 254 with the water inlet 244b of the fuel-water tank 222. The pipes 260 and 262 are provided, respectively, with valves 264 and 266 (both shown in closed position). By the addition of a third horizontal pipe 268 be- 30 tween the upper fuel outlet 246a of the fuel-water tank 220 and the top of the inverted stand pipe 250 of the fuel-water tank 222, I provide for selective water ingress at the water inlet 244a, or water ingress at the water inlet 244b, or water 35 ingress at the bottom of the inverted stand pipe 250, the latter condition obtaining only where the fuel-water tank 220 has become completely filled to overflowing with liquid A (i. e., water).

Interconnection of the fuel-water tanks 220 and 222 with the remainder of the dispensing system shown in Fig. 3 is as follows: The lower fuel outlets 248a and 248b of the fuel-water tanks 220 and 222 are provided with vertically disposed pipes 270 and 272, terminating respectively in 40 valves 274 and 276 (shown in closed position). The upper extremity of the pipe 272 is further provided with a second valve 278 (shown in open position). Both the pipes 270 and 272 are commonly interconnected to a delivery line 280, which 45 is further selectively interconnected with the horizontal pipe 268 by means of a third vertical pipe 282 terminating at its upper end in a three-way valve 284 and at its lower end in a two-way valve 286. A fourth vertically disposed pipe 288 operatively connects the upper fuel outlet 246b with the delivery line 280. It is provided with a valve 290 (shown in open position) at its lower extremity.

While the combination auxiliary tank and fuel 50 level signal device 226 is shown and described in detail in connection with Fig. 8, general reference to its diagrammatic showing in Fig. 3 is deemed desirable at this point.

The segregator 224 is composed of a metering 55 element 292 and a segregator element 294. The former consists of a casing 296 provided with a liquid inlet 298, a stand pipe 300 and a vent line 302. It will be noted that that portion of the stand pipe 300 which projects through the bottom 60

of the casing 296 forms an upper liquid inlet 304 for the segregator element 294. The stand pipe 300 is further provided with a valve 414 (shown in open position) and a small orifice 308 flush with the inner bottom of the casing 296, the special purpose of which is discussed below. In addition to the upper inlet 304, a casing portion 308 of the segregator element 294 is provided with an upper liquid outlet 310, a lower liquid inlet 312, a lower liquid outlet 314 and a float 316 (momentarily indicated as seated within and therefore closing the lower fluid outlet 314). The outlet 310 is connected to one end of a horizontal pipe 318 provided with a valve 320 (shown in open position).
 15 The combination auxiliary tank and fuel level signal device 226 is composed of an auxiliary tank element 322 and a signaling element 324. The former element consists of a casing 326 provided with an upper fuel inlet 328 (connected to the other end of the horizontal pipe 318) and an inner fuel container 330 having a pivoted supporting arm 332. The casing 326 is also provided with a lower fuel outlet 334. The latter element consists of a fume proof switch 336 in operating contact with the supporting arm 332, a battery 338 and a lamp 340. The latter two parts are electrically connected in series to two binding ports provided at the top of the switch 336. The fuel outlet 334 of the casing 326 is connected to the inlet portion of the engine carburetor 214 by means of a horizontal pipe 342 provided with a throttle valve 344.

Before proceeding with a description of the various operating characteristics of the dispensing system shown in Fig. 3, certain details of Fig. 8, as well as interconnection of the fuel-water tanks 220 and 222 to the segregator element 294, require brief description. Attention need only be directed to the upper half of the auxiliary tank element 322 of the combination auxiliary tank and fuel level signal device 226 of Fig. 3 (as detailed in Fig. 8). The uppermost portion of the casing 326 is provided with an annular shoulder 346 adapted to receive a removable top plate 348 and a plate gasket 350. An upwardly projecting pipe boss 352, an upstanding switch housing 354 and depending pivot bosses 356 form an integral part of the top plate 348. Screws 358 are utilized to secure the top plate 348 to the annular shoulder 346.

The inner fuel container 330 consists of a lower half 360a having a fuel ingress-egress opening 362 at its bottom central portion and an upper half 360b having an air egress opening 364 at its top central portion. The latter opening is made up of a valve well 366 having a flat valve seat 368 upon which loosely rests a relatively thin valve disc 370. This arrangement permits liquid to readily enter the inner fuel container 330 through the fuel opening 362 (due to unresisted upward escape of the trapped air through the air opening 364). Thereafter, so long as the opening 362 remains liquid-sealed, seating of the valve disc 370 will prevent egress of liquid trapped within the container 330. A pin 372 passed through the upper wall portion of the valve well 366 serves the dual purpose of limiting upward travel of the valve disc 370 and of providing pivotal attachment between the container 330 and the yoked 70 left extremity of the supporting arm 332. A second pin 374, secured to the pivot bosses 356, completes attachment of the container 330 and its supporting arm 332 to the under surface of the top plate 348. Just prior to assembly of the above 75 parts, as indicated in Fig. 8, a sieve 376 is loosely

positioned in a recess 378 provided in the top inner surface of the annular shoulder 346. In order to assure ready ingress of fuel through the upper inlet 328 of the casing 326, it is essential that a vent line 380 in communication with inside of the 5 sieve 376 be provided. A fuel ingress-egress opening 382 is also provided in the stiffener reinforcing the bottom portion of the sieve 376.

The switch element 336 of the combination auxiliary tank and fuel level signal device 226 of 10 Fig. 3 (as detailed in Fig. 8) may be considered as divided into a longitudinal displaceable portion 384 and a fixed head portion 386. The displaceable portion 384 comprises a Sylphon 388 with bottom soldered to a washer 390 and top soldered 15 to the upper inner extremity of the switch housing 354, a central stem 392 (of insulating material), a combination retaining screw and contacting pin 394 (securing the washer 390 to the central stem 392), a contactor 396 screwed fast to 20 the upper extremity of the central stem 392 and a hold-down spring 398 shouldered against the outer mid portion of the central stem 392. It will be noted that the above arrangement of parts provides an air-tight or fume proof seal between 25 the displaceable portion 384 and the interior of the casing 326. A hole 400 in the bottom of the switch housing 354 permits inward projection of the bottom extremity of the combination retaining screw and contacting pin 394 within the casing 326. The fixed head portion 386 comprises a cover cap 402, a cover cap retaining pin 404, insulated binding posts 406 and inwardly projecting contactor springs 408 electrically connected to the aforesaid insulated binding posts 406. The latter binding posts and contactor springs are held fast to the cover cap 402 by means of a washer-like insulation 410 provided with a central opening 412 permitting upward movement of the contactor 396 against the oppositely disposed 40 (and normally open) ends of the contactor springs 408. When assembled, the spring 398 exerts just sufficient downward pressure upon the longitudinal displaceable portion 384 to retain the inner fuel container 330 in the position indicated 45 in Fig. 8 when empty or so long as the interior and exterior portions of the container are completely liquid surrounded. On the other hand, when egress of fuel through the fuel outlet 310 is stopped, as indicated in Fig. 10, ingress of fuel 50 through the inlet 328 of the casing 326 simultaneously ceases and the level of the fuel without the container 330 gradually lowers with respect to the fuel trapped within the container 330, causing 55 gradual sinking of the outer fuel to within proximity of the level 4 indicated in Fig. 10, whereupon the partially unsupported container 330 sufficiently sinks within the auxiliary tank element 322 to cause the open ends of the contactor springs 408 to be closed by the contactor 396, resulting in lighting of the lamp 340. Operation of the signaling element 324 prior to unsealing of the opening 362 in the bottom of the inner fuel container 330 is essential, in order that proper utilization may be made of the auxiliary fuel supply still remaining within the container 330.

The fuel-water tanks 220 and 222 are interconnected with the bottom of the segregation element 294 in the following manner: The lower liquid inlet 312 of the casing 308 is directly connected to a short vertical pipe 416 provided with a two-way valve 418 (shown closed with reference to the upper portion of the pipe 416). A double L-shaped pipe 420 is connected at its horizontal end to the left side of the two-way valve 418 and 75

at its two vertical ends to the bottoms of the valves 274 and 276 (shown in closed position). With the valve 278 in the open position of Fig. 3, additional opening of the valves 274 and 276, in combination with 135 degree clockwise rotation of the two-way valve 418, will place the interiors of the fuel-water tanks 220 and 222 and the casing 308 in direct intercommunication. As was the case with the segregator 18 of Fig. 1, the lower liquid outlet 314 of the casing 308 is provided with a short horizontal pipe 422, a discharge tube 424 and a valve 426 (closed).

The operations of the fuel dispensing system shown in Figs. 3, 9 and 10 are described with reference to four distinct "tank conditions." Assuming, in each of the above "conditions," that all one-way valves forming a part of the system of pipe lines-controls 228 are initially closed, these operations are as follows:

20 *Tanks under "take-off" condition*

Let it be assumed that a lighter-than-air craft equipped with the dispensing system of Fig. 3 is secured for the first time to a mooring mast, 25 awaiting preparation for take-off, and that under this initial condition all of the liquid containers shown in Fig. 3 are empty. Filling of the empty containers then resolves itself into three stages; i. e., placement of water in the ballast tank 216, 30 placement of gasoline in the fuel-water tanks 220 and 222 and placement of gasoline in the remaining containers of Fig. 3, which latter step includes introduction of a small quantity of water in the bottom of the segregator 224.

35 Firstly, having opened the valve 256 of the water ballast tank 216, a mechanic thereafter removes the filler cap 234 and supplies the tank 216 with sufficient water (i. e., liquid A) to bring about the previously mentioned liquid level l_1 . 40 Secondly, the mechanic positions the three-way valve 284 and the two-way valve 286 (between tanks 220 and 222) in the manner shown in Fig. 3, removes the combination filler cap-float controlled overflow 242a from the fuel-water tank 45 220 and fills the latter with gasoline (i. e., liquid B). Thirdly, the mechanic rotates the valve 284, 180 degrees, rotates the valve 286, 90 degrees clockwise of the showing of Fig. 3, opens the valves 278, 290 and 320, removes the combination 50 filler cap-float controlled overflow 242b of the fuel-water tank 222 and removes the vent line 302 from the casing 296 of the metering element 292. After introducing sufficient water within the casing 308 of the segregator element 55 294 to create the liquid level l_2 and replacing the the vent line 302 of the metering element 292, the mechanic executes the final stage of empty container filling. Proceeding slowly, at first, he introduces gasoline into the fuel-water tank 222.

60 Due to top venting of the casing 296, the gasoline so introduced readily flows through the pipes 272 and 280 to the base of the casing 296. There the flow separates, a limited quantity (i. e., a quantity comparable to the water overflow provisions 65 of the segregator element 294) passing through orifice 306 and the remainder flowing up the sides of the casing 296 until it "spills over" the top level l_2 of the stand pipe 300, down the sides of the latter, through the inlet 304 then across the 70 top of the float 316 then through the outlet 310 (all of the segregator element 294), through the pipe 318 until it "spills over" into the inlet 328 of the vented auxiliary tank element 322, through the outlet 334 of the latter into the pipe 342 and 75 through the throttle valve 344 into the carburetor

214. As soon as the carburetor 214 is full, newly introduced gasoline remains within the tank element 322 until the casing 326 and the inner container 330 are completely filled. Thereafter, newly introduced gasoline will remain within the 5 fuel-water tank 222 until it is completely filled. The orifice 306 serves to retard surplus water entry into the segregator element 294 until egress of all fuel below the level l_2 has been accomplished. It is of sufficient size to continuously 10 pass quantities of water up to the capacity of the overflow tube 424.

I wish to particularly note, at this point, that the valve and container adjustments described above pertain solely to "tank filling" operations 15 and not to flight operating conditions.

20 *Tanks under "one-fourth completed flight" condition*

From prior to unmooring up to one-half completed flight, a lighter-than-air craft equipped with the dispensing system of Fig. 3 can continue to utilize the like valve settings of Figs. 9 and 10. That two additional "settings" can equally well be 25 utilized is further explained below. Basic principles of operation are identical for all three "settings."

In Figs. 9 and 10, I desire to hold the fuel-water tank 222 in reserve and to deliver gasoline contained in the fuel-water tank 220 directly to the carburetor 214 (through the segregator 224 and the combination auxiliary tank and fuel level signal 226). I therefore first indicate as open (in Fig. 9) the valves 256 and 264 in the bottoms, respectively, of the water ballast tank 216 and the fuel-water tank 220. I further indicate that adjustment of the valves 284 and 286 (located between the fuel-water tanks 220 and 222) which will commonly interconnect the upper fuel outlet 246a, the vertical pipe 282 and the fuel delivery line 280. With unmooring of the above craft, moisture collecting in the water recovery system 212 is pumped into the water ballast tank 216. As the flight proceeds, the initial level l_1 of the water (i. e., liquid A) remains relatively constant. With the valve "setting" of Figs. 9 and 10, an approximate minimum head h_2 of water is continuously available to assure from partial to complete egress of gasoline (i. e., liquid B) from the fuel-water tank 220. Should this become too low, gravitational delivery of fuel may be effected through appropriate adjustment of valve 286.

I mentioned, above, two further valve "settings" possible with the tanks and system of pipe line-controls illustrated in Figs. 9 and 10. Firstly, upon attainment of the one-half completed flight condition of Fig. 10, the valves 284 and 286 may be rotated 90 degrees in a counter-clockwise direction and the valve 290 opened. The new valve adjustment will cause ingress of water (i. e., liquid A) down the stand pipe 250, resulting in corresponding egress of gasoline (i. e., liquid B) from the upper fuel outlet 246b directly to the 65 carburetor 214 (through the segregator 224 and the combination auxiliary tank and fuel level signal 226). Secondly, instead of initially opening the valve 264, the valves 266 and 290 may be opened. Then with retention of the 284 and 286 70 valve "setting" of Fig. 3, egress of gasoline from the upper fuel outlet 246b directly to the carburetor 214 will occur (through the segregator 224 and the combination auxiliary tank and fuel level signal 226).

Tanks under "one-half completed flight" condition

Immediately following attainment of the above flight condition, egress of water (i. e., liquid A) from the fuel-water tank 220 displaces gasoline (i. e., liquid B) previously occupying the delivery line 280, the lower portion of the casing 296, and the upper portion of the casing 308, resulting in upward movement of the float 316 and closing 5 of the fuel outlet 310 of the segregator 224 (as shown in Fig. 10). Thereafter, the gasoline contained in the combination auxiliary tank and fuel level signal device 226 remains the sole fuel source for the carburetor 214. As previously described in connection with Figs. 8 and 10, dropping of the gasoline to the level 4 lights the lamp 340 of combination auxiliary tank and fuel level signal device 226. Immediate steps must thereafter be taken to rotate the valves 284 and 286, 10 90 degrees counter-clockwise of their showing in Fig. 10 and to open the valve 290 (as previously described under the First valve "resetting" of the paragraph immediately above).

With the above valve "resetting," water will 25 commence to drain through the overflow 424, permitting ingress of gasoline within the casing 296 of the segregator 224. Simultaneously, the level 4 of the gasoline remaining without the inner container 330 will continue to drop until the opening 362 in the bottom thereof is uncovered. Thereafter, the contents of the container 330 will be gradually fed into the bottom of the combination auxiliary tank and fuel level signal device 226 until ample time has elapsed for the 30 water remaining in the casing 308 of the segregator 224 to return to the level 4 of Figs. 3 and 9. Gasoline egress from the fuel outlet 310 is now re-established.

Tanks under "completed flight" condition

At the commencement of my description of the operation of the fuel dispensing system of Figs. 3, 9 and 10, I assumed for "take-off" condition that a newly constructed lighter-than-air craft 45 was being "serviced" for the first time at its mooring mast. Under such conditions, neither water nor gasoline would be present in the fuel-water tanks 220 and 222 and no useful purpose would have been served by premature utilization of the 50 gasoline fill line 230.

Upon return to its mooring mast from this initial or subsequent long flights, the above lighter-than-air craft has the tank appearance of Fig. 10, if it be additionally assumed that all gasoline 55 aboard is consumed with the single exception of the showing of the auxiliary tank element 322 (i. e., change the gasoline of tank 222 to water). It is now desired to refill the fuel-water tanks with gasoline. This is done as follows:

First method

In this preferred method, the three-way valve 284 is rotated 90 degrees counter-clockwise and the two-way valves 286 and 418 are rotated 45 degrees counter-clockwise and 135 degrees clockwise (respectively) of the showing of Fig. 10. Thereafter, valves 264, 266 and 414 are closed and valves 232, 274, 276, 278, 290 and 426 are opened. Thereupon, ingress of gasoline from the fill line 230 will cause downward receding of water formerly occupying the fuel-water tanks 220 and 222, the vertical pipes 282 and 288, the inverted stand pipe 250, the pipes 270 and 272, the casing 296 and finally the double L-shaped pipe 420;

since the aforesaid water may readily escape up the vertical pipe 416 through the segregator element 294 (whose float 316 has previously attained the "up" position of Fig. 10) and the horizontal pipe 422 to awaiting ground drain pipes or waste 5 containers. The segregator element 294 automatically shuts off with ingress of gasoline.

Second method

If desired, upon return to the mooring mast, 10 the valve adjustments of the preceding paragraph may be re-accomplished with the dual exception that valves 232 and 418 remain momentarily as positioned in Fig. 10. The combination filler cap-float controlled overflows 242a and 242b, 15 will first permit ready drainage of water through the bottom of the vertical pipe 416, then with closure of valves 274 and 276, permit the gasoline ingress for the tanks under take-off condition already fully described in preceding paragraphs. 20

It has been previously stated, at the commencement of this specification, that the third embodiment of my invention, as illustrated in Fig. 4, consists of applying the new and novel double acting segregation features illustrated above to 25 the improvements in fluid dispensing apparatus disclosed in my Patent No. 2,120,266, issued June 14, 1938. For that reason, it has only been necessary for me to reproduce the lower portion of Fig. 1 of the above patent with appropriate double 30 acting segregation modification.

I re-employ, without modification, the entire "upper portion" of the fluid dispensing apparatus generally indicated by the letter "B" of said Fig. 1; i. e., the "upper or secondary segregator 11," 35 the "metering means 13" and the "discharge mechanism 14." I omit the "motor driven pump 12" of said Fig. 1, as city water pressure accomplishes its function in the third embodiment of my invention. Since over half of the parts illustrated in (new) Fig. 4 are a duplication of like parts in said Fig. 1, original number designations (raised to the "five-hundred" series) have been retained. Where new parts are utilized, normal numbering is continued. 45

The lower segregator 518 includes a float chamber 518, a float 519 disposed within said chamber, a lower needle valve 520 and an upper needle valve 521, both of which are operatively connected to and controlled by the float 519. The float 50 chamber 518 further incorporates a lower outlet passage 522 against which the lower needle valve 520 is adapted to seat and a new lower inlet passage 462. The passageway 522 embodies a discharge tube 524 incorporating a check-valve 55 525 which is constructed in accordance with the teaching set forth in my Patent No. 2,047,229, issued July 14, 1936, and which operates to trap a predetermined head of the heavier or undesirable component in the float chamber and to obtain an 60 automatic and intermittent segregation of such undesirable component from the float chamber when the combined head of the lighter and heavier components in the float chamber is greater than a predetermined value. 65

The float chamber 518 further embodies an upper outlet passage 526 which is connected to a fuel delivery pipe 529. The latter part is in turn connected at its upper end with a "fluid receiving or storing chamber 30," forming a part 70 of the "upper segregator 11," described in my aforementioned Patent No. 2,120,266.

As was the case in the first embodiment of my invention, I employ as principal elements of my third embodiment as underground storage tank 75

500A, a gasoline fill line 464 from a nearby tank car or truck siding (not shown), a water pressure line 466, a water drain line 468, and a system of pipe lines-controls 470 associated therewith, all 5 duplicating the functions performed by the tank 10, the filler line 14, the pressure line 16, the drain line 56, and the pipe lines-controls 18 of Fig. 1.

The auxiliary parts associated with the above 10 principal elements are as follows: An inverted stand pipe 472 (performing the same function as the stand pipe 20 of Fig. 1), extends from the bottom of the tank 500A through its top surface and into the lower inlet passage 462 of the lower 15 segregator 510. It is provided with an upturned lower portion 474, a by-pass line 476 terminating in the drain line 468 and including a pressure relief valve 478, and a two-way valve 480. The valve 480 is further connected to the water pressure line 466 through a pressure regulator 482 (performing the same function as the pressure regulator 34 of Fig. 1).

An opening 484 in the upper portion of the tank 500A is rendered selectively interconnectible 25 with a pipe 515 or the fill line 464 by means of a second two-way valve 486. The upper end of the pipe 515 terminates in an upper inlet passage 516. A third shut-off valve 488 is located in the lower outlet passage 522 immediately beneath 30 the check-valve 525. It should be noted, at this point, that I anticipate simultaneously and automatic dual adjustments of the valves 480, 486 and 488; i. e., one adjustment for accomplishing drainage of a water filled storage tank by ingress 35 of fresh gasoline and the other adjustment for accomplishing fuel delivery from a gasoline filled storage tank.

If desired, additional mechanical or electrical automatic adjustment of the above three valves 40 may be accomplished through operative interconnection of the valves with a conventional fuel level gauge composed of a float element 490 located within the tank 500A and a dial element 492 recessed within a platform 494 supporting 45 the upper portion of the fuel dispensing apparatus generally designated as 500B. In the showing of Fig. 4, the water (i. e., liquid A) and the gasoline (i. e., liquid B) contained within the tank 500A has risen to its maximum "up" level l_8 , 50 constituting what I have already designated as water filled tank condition. Through operative interconnection of a control mechanism (not shown) located within the dial element 492 to the float element 490 by means of a link mechanism 496 and to the valves 480, 486 and 488 by 55 means of the conduits 498; full line "up" attitude of the float element 490 automatically effects the valve positioning of Fig. 4. On the other hand, attainment of the dot-and-dash "down" attitude 60 of the float element 490 automatically alters the valve positionings of Fig. 4 such that the valves 480 and 486 are repositioned in a counter-clockwise direction 135 degrees and the valve 488 is repositioned in the same direction 90 degrees. 65 The significance of both changes becomes readily apparent from the paragraph which immediately follows.

It should be distinctly understood that the automatic valve adjustment described in the above 70 paragraph is not essential to the basic operation of the third embodiment of my invention. For that reason the operations of the fuel dispensing system shown in Fig. 4 are described with reference to two "tank conditions," since it is at 75 once obvious that simple disconnection of the

conduits 498 operatively joining the fuel level gauge with the above three valves makes possible direct manual adjustment of said valves such that any desired quantity of gasoline (i. e., liquid B) or water (i. e., liquid A) may be introduced into the underground storage tank 500A.

Water filled storage tank

Let it be assumed that ingress of water in the tank 500A has reached a condition such that the 10 joining liquid level l_6 obtains, and that further water ingress is not desired. The valves 480, 486 and 488 are simply manually adjusted into the positions indicated in Fig. 4. The foregoing valve settings accomplish two results; i. e., they 15 provide for unobstructed egress of water through the inverted stand pipe 472, the lower inlet passage 462, the float chamber 518, and the lower outlet passage 522 (incoming water having raised the present showing of segregating level l_{10} , in 20 Fig. 4) to the water drain line 468 and they also provide for ingress of a constantly increasing top layer of gasoline through the gasoline fill line 464 and the opening 484 provided in the top of the tank 500A. Ejection of water continues until 25 the top layer of gasoline reaches the open mouth of the upturned lower portion 474 (of the stand pipe 472). Then, for a very brief period, a mixture of water and gasoline will enter the bottom of the lower segregator 510 until a sufficient 30 quantity of the latter causes the lower needle valve 520 to seat (as shown in Fig. 4), thus cutting off further fluid flow through the lower outlet passage 522.

If I so desire, I may readily substitute in lieu of the automatic action of my double acting segregator, the valve adjustment described two paragraphs above. Then dropping of the float element 490 to the dash-and-dash positioning of Fig. 4 automatically rotates the valves 480 and 486, 135 degrees (counter-clockwise of the showing of Fig. 4) as well as effects a 90 degree rotation of the remaining valve 488 (as previously noted above) and further water egress ceases.

Gasoline filled storage tank

The valve resettings of the preceding paragraph (whether manual or automatic) accomplish two results; i. e., they provide for unobstructed egress of gasoline through the opening 50 484 provided in the top of the tank 500A, the pipe 515 (since valve 486 is positioned to cut-off fluid ingress with respect to the fill line 464), the upper inlet passage 516, the float chamber 518 and the upper outlet passage 526 to the fuel 55 delivery pipe 529 and they also provide for ingress of water from the water pressure line 466 through the pressure regulator 482, the inverted stand pipe 472 (since the valve 480 is positioned to cut off fluid ingress with respect to the upper 60 portion of the pipe 472 and the lower inlet passage 462 of the lower segregator 510) to the underground storage tank 500A. Thereafter, continuous delivery of gasoline from the discharge mechanism 14 of my Patent No. 2,120,266 will 65 effect steady rising of the dot-and-dash level l_9 shown in Fig. 4 until it ultimately attains the full line positioning of level l_8 .

Having now fully described my invention what I claim as new and desire to secure by Letters 70 Patent, is:

1. In a dispensing system in which liquids of different densities are dispensable by the displacement of either liquid by the other comprising, in combination, a tank adapted to receive

said liquids and having two outlets arranged at different elevations to enable the displacement of either liquid by the other, means forming a chamber having an inlet and an outlet disposed at one elevation and a further inlet and a further outlet disposed at a different elevation, each tank outlet being communicatively connected with a chamber inlet of like elevation, means between each chamber inlet and its connecting tank outlet for selectively controlling liquid flow therethrough, and density responsive valve means in said chamber means for limiting fluid egress to the displaced liquid.

2. In a dispensing system in which liquids of different densities are dispensable by the displacement of either liquid by the other comprising, in combination, a plurality of tanks, each tank being adapted to receive said liquids and having two outlets arranged at different elevations to enable the displacement from said tanks of either liquid by the other, means forming a chamber having an inlet and an outlet disposed at one elevation and a further inlet and a further outlet disposed at a different elevation, all tank outlets of like elevation being communicatively connected with a chamber inlet of like elevation, means between each chamber inlet and its connecting tank outlets for selectively controlling liquid flow therethrough, and density responsive valve means in said chamber means operable to prevent egress of either one of said liquids through its appropriate chamber outlet so long as the same constitutes the displacing liquid.

3. In a dispensing system in which liquids of different densities are dispensable by the displacement of either liquid by the other comprising, in combination, a plurality of tanks, each

tank being adapted to receive said liquids and having two outlets arranged at different elevations to enable the displacement from said tanks of either liquid by the other, means forming a chamber having an inlet and an outlet disposed at one elevation and a further inlet and a further outlet disposed at a different elevation, all tank outlets of like elevation being communicatively connected with a chamber inlet of like elevation, means between each chamber inlet and its connecting tank outlets for selectively controlling liquid flow therethrough, and density responsive valve means in said chamber means for automatically limiting fluid egress to the displaced liquid.

4. In a power plant provided with a water recovery system, means utilizing the water recovered by said system for supplying fuel to said power plant comprising, in combination, one or more fuel tanks, each tank having an inlet and two outlets, said outlets being arranged at different elevations to enable the displacement of fuel by water or vice versa, means for supplying water or gas to effect said displacements, means forming a chamber having an inlet and an outlet disposed at one elevation and a further inlet and a further outlet disposed at a different elevation, all tank outlets of like elevation being communicatively connected with a chamber inlet of like elevation, means between each chamber inlet and its connecting tank outlets for selectively controlling liquid flow therethrough, and density responsive valve means in said chamber means operable to prevent egress of either one of said liquids through its appropriate chamber outlet so long as the same constitutes the displacing liquid.

DAVID SAMIRAN.
